Related U.S. Application Data

The ornamental design for a cap and a container with a product having a stripe, as shown and described.

(63) Continuation of application No. 29/207,404, filed on Jun. 14, 2004, now Pat. No. Des. 548,599.

DESCRIPTION

(51) **LOC (8) Cl.** **09-01**

FIG. 1 is a perspective view of a cap and a container with a product having a stripe showing my new design;

(52) **U.S. Cl.** **D9/516**; D9/521; D9/520;

FIG. 2 is a front view thereof;

D9/529; D9/549; D9/552

FIG. 3 is a bottom plan view thereof;

(58) **Field of Classification Search** D9/516,
D9/521, 529, 549, 552, 565, 567, 575, 434,
D9/556, 569; 215/381-385

FIG. 4 is a left side view thereof;

See application file for complete search history.

FIG. 5 is a back view thereof;

(56) **References Cited**

FIG. 6 is a right side view thereof;

FIG. 7 is a top plan view thereof;
